UNITED STATES PATENT OFFICE.

JAMES C. PATTEN, OF KOKOMO, INDIANA, ASSIGNOR TO THE GLOBE STOVE & RANGE COMPANY, OF KOKOMO, INDIANA.

DESIGN FOR AN ELECTRIC RANGE.

48,193.

Specification for Design.

Patented Nov. 23, 1915.

Application filed May 3, 1915. Serial No. 25,620. Term of patent 7 years.

To all whom it may concern:

Be it known that I, JAMES C. PATTEN, a citizen of the United States, residing at the city of Kokomo, county of Howard, State of Indiana, have invented a new, original, and ornamental Design for Electric Ranges, of which the following is a specification, reference being had to the accompanying drawing, forming a part thereof, in which the single figure of the drawing is a perspective

view of an electric range, showing my new design.

I claim,

The ornamental design for an electric range, as shown.

JAMES C. PATTEN.
